UNITED STATES PATENT OFFICE.

FRANCIS J. DOYLE, OF CHICAGO, ILLINOIS.

FURNACE.

1,107,594.

Specification of Letters Patent. Patented Aug. 18, 1914.

Application filed August 15, 1908, Serial No. 448,708. Renewed January 14, 1914. Serial No. 812,155.

To all whom it may concern:

Be it known that I, FRANCIS J. DOYLE, a citizen of the United States, residing at Chicago, in the county of Cook and State of Illinois, have invented certain new and useful Improvements in Furnaces, of which the following is a specification.

This invention relates to improvements in furnaces, more particularly adapted for heating boilers for the generation of steam, although capable of use with suitable modifications for hot air heating or the like.

The generic features of the invention are susceptible of embodiment in portable furnaces, such as are used in locomotives, etc.

Among the salient objects of the invention are, to provide a construction in which the products of combustion of the fuel are more promptly and directly carried into surface contact with the heating surface of the boiler; to provide a construction in which the fire box extends the full length or substantially the full length of the boiler and the products of combustion pass laterally out of the fire chamber directly into the boiler chamber and into contact with the boiler; to provide a construction of the character last referred to which also embodies a continuous reservoir feed of the fuel; to provide a furnace so organized that an effective and very perfect combustion is secured with the aid of only so much draft as will barely convey away the waste gases; to provide a specific embodiment of the invention in which two boilers are heated from a single fuel reservoir, each half of the furnace being capable of use independently of the other or both together, as desired; to provide improvements in the details of construction and arrangement of the furnace mechanism whereby adequate supplies of oxygen are admitted at proper points to insure the most efficient combustion; to provide improvements in the details of construction and arrangement of the boilers which insure a maximum heating surface within a given boiler space, and in general, to provide an improved construction of the character referred to.

The invention consists in the matters hereinafter described and more particularly pointed out in the appended claims, and will be readily understood from the following description, reference being had to the accompanying drawings in which—

Figure 1 is a view partly in end elevation

and partly in transverse vertical section of one embodiment of the invention; Fig. 2 is a horizontal, sectional view taken on an indirect line 2—2 of Fig. 1, and looking downward; Fig. 3 is a longitudinal, vertical section on line 3—3 of Fig. 1, and looking in the direction of the arrow; Fig. 4 is a side elevation of the device and showing more particularly the arrangement of the various air pipes.

Referring to the drawings, 1 designates, as a whole, the masonry structure of the furnace, the same comprising side walls 2 desirably inclined inwardly as to the upper portions as indicated at 2', vertical front and rear end walls 3 and 4, respectively, and a top wall 5 provided centrally with a longitudinally extending opening 6 through which the fuel is admitted and which opening is provided with one or more covers 6'. The lower portions of the side walls 2 are made thick and constructed to provide longitudinally extending air chambers 7 provided with lateral outlet ports 8 and upper outlet ports 9. Each of these air chambers 7 has an inlet port 8'. Across the lower part of the interior of the furnace is arranged an extension grate 10, which is spaced above the floor of the furnace a sufficient distance to form the usual ash-pit 11 below the same.

The interior of the furnace is provided with two longitudinally extending partition walls 12, 12, which extend upwardly from the inner edges of the thickened lower portions of the side walls to the roof of the furnace adjacent to the inlet opening through the latter and are therefore inclined inwardly and upwardly. The space between these partition walls and above the grate constitute the fuel reservoir 13 of the furnace and the two spaces outside of the partitions and above the thickened lower portions of the side walls constitute the two boiler chambers 14, 14.

The partition walls 12 are supported by a series of abutments 15 formed as integral extensions of the thickened side walls, and between these abutments are formed ports 16 (see Fig. 3), which afford communication between the fire chamber, *i. e.*, the lower portions of the fuel reservoir above the grate and said boiler chambers. Pivoted doors 17 are provided for closing the several ports 16; these doors being normally turned back to rest against the inclined bottoms 18 of the boiler chambers.

Within each boiler chamber is arranged a boiler, designated as a whole 19. Any suitable boiler may be employed, but those shown herein are of my own invention and are preferred. Each boiler comprises an upper cylinder or drum 20, a similar lower cylinder or drum 21, and a plurality of communicating tubes 22 spaced apart so as to admit of a free circulation of the gases of combustion around the drums and around the communicating tubes. Each drum may extend into the end wall of the furnace in order to be supported thereby. In order to equalize the steam pressures between the two boilers I preferably connect the same by means of a pipe 23, from which pipe the main steam trunk may lead off as indicated at 24.

In order to prevent the fuel from banking up against the lateral outlet port 8 leading from the air chamber 7 these ports are arranged to open into short vertical open-ended tubes 25 of refractory material, so that the air supply meets the flames at just above the entrance ports between the fire and boiler chambers. Another set of air flues or ducts is provided for delivering air just at the upper sides of the ports 16, comprising a plurality of passages 26 leading up through the side walls of the furnace to and through the upper walls thereof, and communicating with corresponding upright refractory tubes 27, the lower ends of which discharge into the fire chamber adjacent to said port 16. The passages 26 communicate at their lower ends with the outer air through lateral inlets 26'. Other similar passages 28 are formed in the side walls of the furnace and communicate with tubes 29, which extend and discharge within the respective boiler chambers as shown clearly in Fig. 1; it being understood that the passages 26 and 28 are alternated or interspersed so as not to interfere or communicate with each other.

It will be noted that the upper drums 20 of each boiler abut against the side walls of the boiler chamber so that the products of combustion are prevented from passing entirely around the upper boiler. In order to compel the circulation of the products of combustion over the lower surface of the upper drums 20 of each boiler, a partition or wall 30 is interposed and extends longitudinally in the space between the drums of each boiler, so that the products of combustion which pass upwardly along the inner walls 12 are compelled to travel upwardly until they reach the transverse passage 30' at the upper end of the wall 30. In order to compel the products of combustion to perform a back and forth traverse in the space laterally outside of the drums, and the partition 30, a second partition board or wall 31 is arranged to divide this space about mid-way

between the upper and lower drums as shown clearly in Fig. 1. This member 31 is arranged to extend from the rear end wall of the furnace forwardly to a point somewhat short of the front end wall as best seen in Fig. 2. Accordingly the products of combustion that rise and pass through the port 30' are compelled to flow longitudinally to the front end of the furnace, then downwardly through the communicating opening 32 between the space above and below the wall 31 and then back to the rear and out through the chimney 33.

The operation of the device will be apparent from the foregoing description but may be briefly described as follows: As the products of combustion pass through the various ports 16 they will mingle with the incoming air through the ports 25 and will then pass upwardly and mix with the air from the ports 29. Passing thence through the transversely extending ports 30' the products of combustion will perform a back and forth traverse as heretofore described and pass out through the respective chimneys 33. This results from the fact that the products of combustion are baffled by the wall 31, and pass through the port 32 and thence throughout the length of the furnace to the outlet 33. It will be noted that inasmuch as the outlet 33 is relatively small a forced draft is obviated and the products of combustion are held within the boiler chamber until consumed.

From the foregoing it will be seen that I utilize a maximum amount of the heat of combustion instead of permitting it to pass directly out through the chimney as is usually done. The steam may be taken out through the pipe 23 which may be controlled by any suitable valve mechanism.

I claim as my invention:

1. In a furnace, the combination of inner walls forming a compartment, a grate near the bottom of said compartment for supporting fuel to be burned, outer walls forming with the inner walls compartments for receiving boilers to be heated, there being ports through the inner walls at the bases thereof and leading from adjacent said grate into said boiler compartments, the space between said inner walls above said ports constituting a fuel magazine for keeping the grate supplied with fuel, said magazine section being entirely inclosed whereby the gases generated therein upon heating of the fuel can escape only downwardly and through said ports and into the boiler compartments, air conduits terminating adjacent said ports to supply air to the gases flowing through said ports whereby said gases are burned in said boiler compartments, and other air conduits supplying air to said boiler compartments above said ports, the inlet ends of said air conduits

- being below the level of said grate, said conduits extending through the outer walls of the furnace whereby the air flowing therethrough is heated before being delivered.
- 5   2. In a boiler furnace, the combination of inner walls forming a vertical compartment, a grate near the lower end of said compartment for supporting fuel to be burned, the upper part of said compartment forming a
- 10 fuel magazine for keeping the grate supplied with fuel, outer walls coöoperating with said inner walls to form boiler compartments for receiving boilers to be heated, said inner walls adjacent said grate having outlet
- 15 openings for products of combustion and for gases distilled from the coal heated in said
- fuel magazine, air conduits for receiving air supply from below the level of the grate and delivering air at said outlets to mingle with the products of combustion and the gases 20 flowing through said outlets into the boiler compartments, air conduits supplying air at various levels to said boiler compartments, and air conduits extending through the fuel magazine and adapted to distribute air into 25 said magazine and to the gases as they flow from the lower end of said magazine into the outlets.

FRANCIS J. DOYLE.
